UNITED STATES PATENT OFFICE.

JAMES TEMPLE, OF MOORESBURG, PENNSYLVANIA, ASSIGNOR OF ONE-HALF HIS RIGHT TO DANIEL J. ROTE, OF SAME PLACE.

IMPROVEMENT IN CAR-COUPINGS.

Specification forming part of Letters Patent No. 142,059, dated August 19, 1873; application filed June 25, 1873.

To all whom it may concern:

Be it known that I, JAMES TEMPLE, of Mooresburg, in the county of Montour and State of Pennsylvania, have invented certain new and useful Improvements in Car-Couplers; and I do hereby declare the following to be a full, clear, and exact description thereof, reference being had to the accompanying drawings, which make part of this specification, in which—

Figure 1 represents a side elevation of a car-coupler embracing my improvements. Fig. 2 represents a longitudinal vertical section, the coupling-link being removed and the pin in position to couple. Fig. 3 represents a front view of the coupler, showing the pin in the position it occupies when the cars are coupled; and Fig. 4 represents a view of the pin detached, with its guiding-yoke.

My invention relates to car-couplers; and it consists in such a combination and arrangement of the several parts constituting my improvements as that the coupling-pin is supported by the spring-gates in position to couple, and the link is ejected from the draw-head when desired, and guided by said gates in its entrance into the mouth of the draw-head, and is also held by an angular plate in a position to couple onto the next car of the train, all as will be hereinafter more fully set forth.

In the accompanying drawing, A A' represent the draw-head of a railway-car, having the ordinary bell-mouthed or other shaped opening B in the bumper C thereof for the entrance of the link D. Hinged to the rear face of the bumper C are two curved gates, E, which are so located as that they are thrown in contact between the upper and lower timbers A A' of the draw-head by springs E', which are attached also to the rear face of the bumper, and arranged to be always in contact with said gates. F represents the coupling-pin, passing down, when coupling, through holes in both the upper and lower horizontal

timbers A A', and guided in its vertical movements by a yoke, F', which encircles the said timbers A A', and is bolted to said pin F at its upper end, so that it moves with the latter in coupling and uncoupling the cars. On the top face of the lower timber A' of the draw-head is arranged an angular plate of metal, H, which serves to hold the coupling-link in proper position to couple with the next car of the train, whatever may be the height of the draw-head of the car to be coupled, as clearly shown by dotted lines in Fig. 1 of the drawings.

When it is desired to couple cars the pin F is drawn vertically upward until it clears the spring-gates E, which are then forced inward and underneath said pin by the springs E', which gates E support it in position for coupling, as clearly shown in Fig. 2. The link D, entering the aperture B, strikes the gates E, forcing them asunder, which leaves the pin F free to drop down through the link, being guided in such movement by the yoke F', as shown in Figs. 3 and 4. The link passes through the gates and into the draw-head until it strikes the plate H, in the different angles of which it is adjusted to suit the height of the draw-head of the next car to be coupled. If it be desired to drop the coupling-link it is only necessary to withdraw the coupling-pin, and the force of the spring-gates drives the link out without being touched by the attendant.

Having described my invention, I claim—

The combination of the draw-head A A', the spring-gates E, which operate as a support for the coupling-link D and to eject it from the draw-head, the coupling-pin F, guiding-yoke F', and the angular guard H, the whole arranged to operate as set forth.

In testimony whereof I have hereunto signed my name.

Witnesses: JAMES TEMPLE.

DANIEL J. ROTE,
D. C. KELLEM.
